UNITED STATES PATENT OFFICE.

LEO SHLICK, OF BOSTON, MASSACHUSETTS.

BEATING ENGINE.

Original application filed February 17, 1921, Serial No. 445,736. Divided and this application filed February 1, 1927. Serial No. 165,250.

This invention relates to certain improvements in machines for the production of pulp as hereinafter set forth, these improvements being divided out from my application filed February 17, 1921, Serial No. 445,736, which has become Patent 1,623,364.

In the drawings forming part of this specification, Fig. 1 is a side sectional view of portions of a beating engine embodying my improvements. Fig. 2 is a sectional end view through the line 2—2 in Fig. 1.

The numeral 1 designates the tub of the beating engine, 2 the beater roll and 3 the bed-plate. The backfall 4 is provided with an adjustable back-fall plate 5 preferably of metal, whose lower edge is stationary at the foot of the back-fall, but whose upper portion has a leaf 6 bent nearly at right angles thereto, which is located against 20 the face of the back-fall next to the beater roll.

Above the beater roll and back-fall is a hood 7 pivotally supported at 9 and retained in its position relative to the beater roll by 25 lever-arms 10 rigid therewith and resting against shoes 11 attached to the bearing boxes 12, so that an upward jump of the beater roll will correspondingly raise the hood and thereby prevent the beater knives of the roll 30 from striking the edge 13 of the deflector portion 14 of the hood.

Between the edge or lip 13 and the backfall I locate a deflecting curb 15 which is pivotally supported at 16 by screw rods 17 35 descending through the hood 7. By turning the hand wheels 18, the deflector curb can be raised and lowered to suit the character of the work. A screw rod 19 pivoted to an arm 20 projecting from the curb 15, 40 and having a hand wheel 21 exterior of the hood, enables the tip of the curb to be swung toward and from the beater roll.

The section of the hood between the lip 13 and its extremity 22 is made a semi-cylinder in order the better to cause the stock to forcibly descend beyond the back-fall as it is shot upward by the rapidly revolving beater roll. To the extremity 22 there is hinged a curved gate 23 for the purpose 50 of building up a head and thereby increasing the velocity of flow down and away from the back-fall, the curvature serving to prevent eddying and resistance to the flow. The lower edge of this gate board 23 descends below 55 the level of the axis of the beater roll, and

considerably below the level of the crest of the back-fall; and is made sufficiently heavy to hang below the surface of the stock injected into the catch basin 25 at the foot of the back-fall even when the current is flowing swiftly therethrough.

The function of the curb 15 is a very important one in the treatment of certain grades of stock; for, if the back-fall is made high enough to produce the head required, the larger lumps of the stock would fail to surmount the same and would badly retard the work; but, by supplying the curb, the heavy lumps can readily surmount the back-fall which is moderate in height, while the more fluid portion of the stock is shot up and over the curb into contact with the rounded hood 7 and thence along the latter down to the remainder of the stock, thereby giving the desired momentum of flow to the latter. The adjustments of the curb 15 are provided to accommodate the different grades of the stock.

The pivoted gate 23 should not only have its free edge below the level of the crest of the back-fall under normal conditions, but it should be sufficiently heavy to retain such position even against the rush of the stock as it pours down the back-fall and along the channel of the tub. Likewise, its lower edge should be below the level of the axis of the beater roll 2 even when the board 5 of the back-fall has been adjusted to a lower position, in order still further to aid in building up a head for the stock immediately 85 after it leaves the beater roll.

What I claim as my invention is:

1. A beating engine comprising a tub, a beater roll, a back-fall, a hood located above the back-fall, and a deflector located between the back-fall and hood for dividing the stock into upper and lower streams as it issues 95 from the beater roll.

2. A beating engine comprising a tub, a beater roll, a bed-plate, a back-fall, a hood located above the back-fall, and an angularly adjustable deflector located between the back-fall and hood for dividing the stock into upper and lower streams as it issues 100 from the beater roll.

3. A beating engine comprising a beater roll, a back-fall, an angularly adjustable deflector curb located close above said back-fall and presenting its edge close to said beater roll, and means for adjusting said curb to 105 110

vary this distance, said curb being located to divide the stock into upper and lower streams as it issues from the beater roll.

4. A beating engine comprising a beater roll, a back-fall, a hood located above the back-fall and presenting an edge to said roll and pivotally supported at a point above the center line of the roll, an obliquely disposed arm rigid with said hood, and a shoe connected with a bearing box of said roll and acting against said arm to elevate said hood when the roll moves upward.

5. A beating engine comprising a beater roll, a back-fall, a hood presenting an edge 15 to said roll, a deflector curb located between said back-fall and edge, screw rods supporting said curb pivotally, each having an operative hand-wheel, an arm rigid with said curb, and a screw rod and hand-wheel for 20 angularly adjusting said curb, said screw rods passing outward through said hood and the hand-wheels being exterior to the same.

6. A beating engine comprising a tub, a beater roll, a back-fall, and a gate board 25 pivotally supported at its upper edge and having its lower edge below the level of the crest of said back-fall and weighted to keep it submerged below the surface of the flowing stock.

7. A beating engine comprising a tub, a beater roll, a back-fall, and a gate board pivotally supported behind the back-fall on 30 a transverse axis, and curved to present a convex surface toward the back-fall.

8. A beating engine comprising a tub, a beater roll, a back-fall, and an inclined gate presenting its lower edge below the level of the crest of said back-fall, and acting gradually to build up a head for increasing the 35 speed of flow of the stock.

9. A beating engine comprising a tub, a beater roll, a back-fall having an adjustable crest, a catch basin at the foot of the back-fall, and means for regulating the quantity of stock injected into said catch basin. 45

10. A beating engine comprising a tub, a beater roll, a bed-plate, and a back-fall having a metal plate one edge of which is at the foot of the back-fall and the other edge of which is bent to form a curved facing 50 toward the beater roll.

11. A beating engine comprising a tub, a beater roll, a back-fall, a semi-cylindrical hood located above the back-fall with one edge close to the periphery of the roll, 55 means for elevating said edge by the upward movement of said roll, and an angularly adjustable deflector supported by said hood close to the roll between the hood and back-fall. 60

12. A beating engine comprising a tub, a beater roll, a back-fall, a curved hood located above the back-fall with one edge close to the roll, a deflector located between the hood and back-fall, and means for adjusting 65 said deflector both angularly and toward and from the roll.

13. A beating engine comprising a tub, a beater roll, a back-fall, a hood pivotally supported in a line vertically above the axis of 70 the roll and presenting an edge close to the latter, an adjustably supported deflector carried by the hood between the back-fall and hood, and means whereby the upward movement of the roll swings the hood and deflector away from it. 75

In testimony that I claim the foregoing invention, I have hereunto set my hand this 18th day of January, 1927.

LEO SHLICK.
